CLAIM

The ornamental design for a lock cover, as shown and described.

DESCRIPTION

FIG. 1 is an isometric view of a lock cover showing the new design.

FIG. 2 is a second isometric view showing the new design with the cover in the open position and showing a partial view of a lock, the lock being shown in phantom image for the purpose of providing the viewer with an understanding of the use of the lock cover and itself not being part of the claimed design;

FIG. 3 is a front elevation view thereof;

FIG. 4 is a left side elevation view thereof;

FIG. 5 is a right side elevation view thereof;

FIG. 6 is a top plan view thereof; the bottom plan view is a mirror image;

FIG. 7 is a front elevation view of the first embodiment showing the broken line disclosure of the cameo removed from the recess. The depth of the recess is illustrated by the height of the upper section of the side view as shown in FIG. 8.

FIG. 8 is a right side elevation view thereof;

FIG. 9 is a front elevation view showing a second embodiment of the lock cover; and,

FIG. 10 is a right side elevation view thereof; the left side view is a mirror image.

The surface of the article not shown in the drawing or described in the specification forms no part of the claimed design.
